June 1870 2608X 52
Mr. Chapman, assignee of.

S. C. T. S. Patent.

The Schedule referred to in these Letters Patent and making part of the same, containing a description in the words of the said S. C. T. S. himself of his improvement in weaving.

The front posts of the frame are no higher than the transom beams to which they are fastened, the sides of the frame are planed, having tenons to enter the front posts in a square direction, being upright at the other end with tenons to enter the back posts; the back posts are placed oblique (towards) the lay of the back posts & front posts being wide apart, the top end of the back posts being the upper part of the lay - or beater and the lower end being sufficiently oblique, to receive the ends of the yarn beam; from the planks to the back posts a brace is inserted on each side, either straight or curved out, to rest upon the swing of the lay, or beater in weaving. The two back posts are united by a cross bar, one at the top or near as the swing of the lay, will permit the other near the bottom, so far below the yarn beam as to give room for the motion of the shuttle, which are attached to it. The breast beam is formed of three narrow boards; the top board is fastened on the ends of the said posts which support it, the bottom board is inserted at each end into those posts parallel to the top board & about $3\frac{1}{2}$ inches distant from it [a space being between them, sufficient for the movement which impels the shuttle] between the top and bottom boards a narrow board is inserted the whole length, the three being united together, sufficiently firm for a breast beam; the strip of board between is put at the back of the others and must have three mortises through; as will be described in the article describing the throwing the shuttle, the end of the beam will then remain open for the convenience of passing the temples as will be seen in the article on that subject.

2608X 52

The claim of originality for the construction of the frame, is not founded on the difference of shape only, but the peculiar construction of its parts, so as to withstand the action of the loom with the greatest advantage; without exterior loomings; it is likewise founded on the economy of construction, as there are little more than half the pieces which the frame of other improved looms or the common loom requires. The lay or bed is made in the common manner, excepting a method of changing the batten, to place them near together for narrow batten, or further apart, as may suit the width of the warp, or the fancy of the weaver; the front side and end of the shuttle box are fastened together; the end of the shuttle box has one end of the shuttle rod secured firmly to it, the other end of the shuttle rod, is secured by a bended iron, secured on the front of the lay. The shuttle box is fastened to the lay by a screw through its end, into the lay; having a nut at the back of the lay to secure it firmly at that end; the other end is fastened by a screw driven through the side into the bottom of the lay, on the inside of the shuttle box is a steel spring, having its elastic point toward the closed end of the shuttle box, and riveted to the side of the shuttle box; through the side a screw is inserted so as to press upon the spring & make it project from the side of the box; this spring is to stop the recoil of the shuttle on striking the end of the shuttle box; it may be covered with leather or any other substance suitable for the purpose. There is a groove through the under beam of the lay through which the picker blocks play (as in other looms). On the under beam there is also a long wooden spring made fast by one end, the other end having some play in a staple, so that when the spring is pressed it will give way with ease until the staple at the other end stops its elasticity in some degree and renders its power greater; this spring is of use in throwing the shuttle as in the following manner. To throw the shuttle; the motion of the lay as it is thrown back, gives the impelling force to the shuttle, & the change of the threads, gives the alternate direction.

direction from side to side, to effect this, on the front of the breast beam between the top and bottom boards, of which the breast beam is composed a crescent or semicircle is pivoted, the pivot being near the periphery of the semicircle, at the centre of the crescent, on its under side a thick ar hand is fastened to project below the lay or thickness has strong fastened to each of the picked blocks, by means of the groove that wheel the picked blocks slide, in the bottom of the lay, so that the hand being quickly moved toward the end of the lay, would impel the shuttle in the same direction, to give the hand the requisite force, a hook is pivoted at the upper point of the semicircle, which hook plays through mortices in the back of the breast beam and project beneath the lay, so that on catching a hook beneath the lay and drawing the lay back, it will draw the hook out, turning the crescent on its pivot & throw the hand in a contrary direction, then bringing the lay forward and catching the other hook the operation is reversed and the hand thrown back to its former position carrying the shuttle to the other side, to elevate the two hooks successively there are two levers on the back of the breast beam (of the first order) these extend to the front side posts, or so as to clear the edge of the cloth; two other light levers (of the second order) having their fulcrum at the front side posts are connected with the former levers (at the end which clears the cloth) by a strong connecting bar, the light levers being enough to play over the treads of the loom, to which they are attached by a string that when one treadle is pressed down, it draws down the light lever and that drawing down the end of the upper lever, except that hook which moves through it and to prevent an accidental catch of both hooks, a button is secured on the back board of the breast beam which raising by one hook bears down the other. The back board of the breast beam has a long horizontal mortice at its bottom edge for the movement of the hand, above this mortice are two other mortices, wider

at top

at top them at bottom in which the two hooks were which are pivoted into the horns or points of the cradle or cradle and a suitable spring which is fastened on the bottom of the box. This spring provides a jerk or labored impulsion acting on the hook to throw the shuttle. To wind the yarn on the yarn beam regularly & that it more separate than is commonly done, the yarn beam is divided into a number of small divisions, each division having a garter or groove turned in the yarn beam; these grooves are to receive hoops of iron or tin, which are hinged together in two or three pieces so as to clasp round the yarn beam & give it to constitute thin separations in the warp; at where the hoop with a screw holds the circle together, which being taken out, the circle can be opened and removed from between the bodies of yarn which it separated; if three hoops are used, the two spaces are to be filled with warp, the middle hoop is then unhinged and removed to the next division where it being placed, that space between the two hoops is filled and the middle hoop removed to another division; the outside hoop remaining to keep up the yarn square on the beam. When the warp is as wide as the weaver desires then the last hoop is left to keep the selvedge yarn regular. To take the lease with greater certainty of not losing a thread, I have devised the following machine. Two narrow pieces of metal of a conicalous nature (as brass, copper sheet iron or tin) are divided with holes the size of a common knitting needle & about four times that distance asunder. These strips of metal are made fast in a frame horizontal and parallel to each other and a few inches distance apart, so that the holes may be over each other, that wires may play perpendicular in them. Above these metal pieces & parallel to them, two wires are stretched, one on each side, with jacks action made by turning the end of a piece of wire to form a eye, for the thread to pass through, the other end being cut long enough to reach from the ends of wires to a little below the under strip of metal. One of these ends is put into each hole; a board is then made by inserting pins, or else cutting out

but not less than the distance of every other jack apart, which being placed beneath the points of the jacks will raise every other one to receive the yoke of the warp, which is passed thro' from the floor over the two side wires, that the eye of the jack will be held suspended, until the thread breaks; when by the jacks falling on the metal strips, notice will be given of its failure & the eye readily detached which then has broken. The bound being then removed to pass beneath the other half of the jacks, they are raised above the wires and the yoke passed through them; the two alternate blades are then united into a loom. This leading machine being placed at the rear of the loom, the warp can be wound on the yarn beam without removing it from its place and the subdivisions of the yarn beam, with the metal loops, a few loops will be sufficient to warp any width of cloth. When the warp is wound on the yarn beam it is necessary, and quantity should be wound on every part, to ascertain this tally which is applied at the side of the loom. At the end of the yarn beam a pin is driven to project a short distance; every revolution of the yarn beam moves one tooth of a small wheel above, by this pin entering its space, this wheel has a similar pin projecting some distance from its axis, which acts in a similar manner on another wheel placed above that one; if the pin on the axis of the yarn beam, moved a tooth of the tally wheel once in 3 feet and there were ten teeth in that wheel, it would of course revolve once in thirty feet or ten yards; this tally wheel having a similar eccentric pin or tooth to give motion to another tally wheel would give a tally of 100 yards, each of these tally wheels should have a spring or pull to hold them firm without changing until the eccentric pin gives them motion. To wind up the cloth when it is woven a large roller or truck is turned on the end of the yarn beam, a smaller one on the end of the cloth beam; each of these rollers has several grooves for bands, the diameter of the grooves decreasing on one beam and increasing in the opposite roller of the other beam; round these rollers a band is put crossing, beginning to weave with the band on the largest roller of the yarn beam and

and the small roller of the cloth beam; the bearing of the long
staves is upon the yarn which gives motion to the yarn beam; this
and the large roller of the yarn beam & small roller of the cloth beam in
turning will move upon that, so that the cloth is wound on the
upper side of the cloth beam. Should the motion given to the beam
be more than what is necessary to wind up the cloth, the band
will slip round the cloth beam, at the same time keeping the cloth
tight; this band is tightened by a block with a lever to draw it down
as is used in other machinery; to make the band hold tight on the
yarn beam, when it slips on the cloth beam, a fiction roller is placed in the front of
the reeling of the band; having a screw and nut to make it fast on the side of
the loom; this fiction roller being pressed tight against the loose band; will
wind it upon the yarn roller and make it hold firmly on that roller by being
rewound in that position, by the nut on the outside of the frame; this fiction
roller may be screwed tight so as not to turn, or it may be left to turn freely
to take the yarn before it passes through the loom; p; the yarn roller is in the
usual place, but has a covering of cloth or knit web which will be more
regular on its surface without a ridge down. Under this roller is another roller
covered in a similar manner, having a trough underneath to contain
size or paste or any substance with which the yarn is to be sized; one of these
rollers has its center movable that by so much the yarn may be borne hard
together; that when the lower roller turns in the parts of size it will, in its rota-
tion, -

squeeze a sufficient quantity of it into the yarn roller to size the
yarn. Between the yarn roller and the loom a circular brush
is placed to brush the web and lay the fibres smooth, before they pass
the loom. This brush is turned by the motion of the treadles; on the
end of the shaft of the circular brush are two wheels having grooves in each,
each wheel has a click to catch in teeth on the shaft of the circular brush
round which they are to revolve; over the treadles are two coop shafts
pinioned on one side of the loom, directly under the circular brush and
extending to the other side, to play under the false wheel on the brush's
shaft; a cord is made fast to the end of one of the coop shafts and
with a double turn round, one wheel is fastened to the other coop

right

shaft, which another cord is fastened and in the same manner as before
 moves the other wheel in a contrary direction, the end being made
 fast to the other end of shaft; these two shafts are attached to the
 treadles by cords one shaft being attached to each treadle; so that
 when the upper shaft is pulled down by a treadle it turns me whire
 forward and gives motion to the brush and turns the other whire
 back to take a fresh hold with the click, of the teeth on the shaft.
 The axis of the circular brush, projects beyond the outside of the
 frame, where it is square, to receive another wheel for guiding or
 winding spools which will be more regularly described here-
 after. The temples instead of being movable and put above the cloth to
 stretch it, as in common looms, are in this loom put under the cloth
 & screwed to the breast beam. each temple consists of a circular
 ring of metal, having sharp teeth, on the flat of the ring, which
 stand angular to its surface and do not take hold when the ring
 is turned one way but turn very easily when the ring is turned
 the other way these teeth, likewise are angularly bent outward
 from a vertical position. A cap is put over the ring which covers
 more than one half of it. this cap is screwed to the bottom, which
 has two flat lips with a groove in each lip, for receiving a screw
 that the lips may be screwed firmly on the breast beam and capable
 of being easily altered; there is likewise a groove in the breast beam
 parallel to its edges; through which the same screw enters, which holds the
 temple, having with or thumb-screw below which will hold the
 temple- case in any place or position which the width of the cloth
 or the contraction of its filling may require, on the inside of the case
 is a pale spring to hold out the teeth on the circumference of the temple and secure
 its rotative motion. These temples with the cases are let into the upper
 board of the breast beam, so that the cloth may pass over them
 even and smooth. the uncoated teeth of the temples are placed
 towards the side of the loom; to force the cloth down upon the
 teeth a clasp or cover is hinged on a projecting lip or piece which
 has a circular gutter under which the teeth of the temple may
 turn easily, without being touched. There is also a screw
 in this

in this is lowered the hinged by which it may be held down. To use these temples, place them at the distance which your cloth is to be distended, put the selvedge on the teeth & then draw the clasp to hold it firm; then commence weaving and as the cloth is made it is drawn toward the heddles because it will pass under the clasp and seize on the oblique teeth and by compelling the temples to turn, the cloth will be stretched out; the two temples being made to stand equal by, on the end of the axis of the circular brush (outside the frame) is a wheel fastened on the axis to turn with it; this wheel is about the same size of the false whir which gives motion to the brush, on the side of this wheel is a hub having grooves for a band, one groove being larger than another; there is another whir similar to this placed horizontally a ^{small} distance from it. a band is passed round the whir on the circular brush and round the hub of the other whir, to give a multiplying motion to its whir; from this whir a band is passed round a small whir ^{and spindle} and which is placed nearly between the two whirs; on the spindle a quill or spool is put for the filling to be wound on it. To wind the filling regularly on the quill or spool, it is threaded through an eye at the end of a swinging bar, which is suspended above, from a piece attached to the loom; at a medium distance between the place of suspension and the eye, a revolving arm is situated whose progressive turn may beat against the swinging bar and regulate the motion along the side of the spool. The blades or swifts on which the yarn is extended are made of four light elastic arms a little thicker than that which is used for baskets; the end of each arm is turned downward at right angle to the shaft and its point bent outward to prevent the yarn from slipping off; at the crossing of these blades a hub is put having a hole through it, to admit a spindle freely, on the top of the

hub

humb a piece of metal is fastened that the point of the spindle, may support the swifts; on the under side of the hub another piece of metal is fastened, having a hole through for the spindle to enter and keep the arms of the swifts horizontal; the yam being extended over these swifts by their elasticity and threaded through the eye of the pendulum and then wound round the spool is by the aforesaid operation wound regularly on the spool, for filling or wrapping the band may be changeable to suit any method of winding; to wind on a long spool or a short one; or to wind long over the spool or very close on the axis of the case a small wheel is fastened, with various sized grooves; round this wheel, round the case a band is passed and around the hub of the wheel on the axis of the circular brush, which gives it a slow motion to regulate the winding of the yam upon the quill or spool.
